CONTROL DEVICE

John E. Renholdt, Bridgeport, Conn., assignor to
 Dictaphone Corporation, New York, N. Y., a
 corporation of New York

Application November 5, 1931, Serial No. 573,133

2 Claims. (Cl. 60—62.6)

This invention relates to control means, and with regard to certain more specific features to foot-operated control means for phonographs or the like.

- 5 An object of the invention is to provide a foot-operated control device the operation of which is not inherently tiring to the operator's foot. Another object is to provide a device of the nature described which may be operated by the 10 toe portion of an operator's foot while said toe portion is raised only slightly above the floor. Another object is to provide a device which is duplex and in which both controls are operable with one motion of the operator's foot, and which 15 may also be operated selectively by the operator's foot. Another object of the invention is the provision of a control device of the nature described which aids the operator in correctly positioning his or her foot on the desired control. 20
- 20 Another object of the invention is to provide a control device of the nature described in which certain parts tend to assume their inoperative position by the force of gravity. Another object is to provide a foot-operated control means in 25 which certain improvements have been effected to eliminate leaks and the like.

Another object of the invention is to provide a control device of the nature described in which the various conduits associated with the device 30 are affixed to the device in an improved manner.

Another object of the invention is to provide a control device of the nature described which is strong and adapted to withstand abnormal pressure of an operator's foot.

35 A further object of the invention is to provide a foot-operated control device which is easily assembled and easily disassembled for repair, which is simple to manufacture, and which comprises a compact structure of neat appearance.

40 Other objects will be in part obvious and in part pointed out hereinafter.

The invention accordingly consists in the features of construction, combinations of elements, and arrangements of parts as will be exemplified 45 in the structure to be hereinafter described and the scope of the application of which will be indicated in the following claims.

In the accompanying drawing, in which is 50 shown one or more of the various possible embodiments of this invention,

Fig. 1 is a top plan view of a foot-operated control device embodying the invention;

Fig. 2 is a front elevation of the control device of Fig. 1 and showing a pedal portion in "operating" position;

Fig. 3 is a detail section taken on line 3—3 of Fig. 1 and showing a compressing means; and,

Fig. 4 is a detail section taken on line 4—4 of Fig. 2, and showing certain parts in plan, and certain other parts in section.

5 Corresponding reference characters indicate corresponding parts throughout the several views of the drawing.

Referring now more particularly to Figs. 1 and 2 there is shown a foot-operated control device comprising a base 1 on which are mounted duplicate air-compressing units or control means 3 and 5 respectively. A duplex flexible conduit 7 is connected to the compressing means 3 and 5, and is adapted to connect the control device 10 to a machine to be controlled. Such a device utilizes compressed fluid (for example air) to control the mechanism of machines, such as transcribing machines, accounting machines and the like, which machines have means associated 15 with them which are responsive to the air pressure created by the control devices. However, the control devices which have been provided heretofore for the operators of transcribing machines and the like, have been so constructed 20 that in use the toe of the operator's foot was raised considerably above the floor, and held in an unnatural and tiring position. Long continuous operation was, therefore, tiring to the operator because of the cramping of muscles due 25 to this unnatural position.

The present invention overcomes the aforementioned previous disadvantages of the foot-operated control means and provides a control 30 means which is operated with an operator's foot 35 in a substantially natural position.

Referring now to Fig. 3, each compressor 3 and 40 5 comprises an inverted cup-shaped housing 9 in which a piston 11 is slidably mounted for reciprocation. Each housing 9 is securely mounted on the base 1 by means of counter-sunk machine screws 8. The piston 11 is ground, or otherwise finished, to provide a substantially air-tight fit between the piston and housing, when the 45 surfaces are properly lubricated. Thus as the piston 11 is moved toward the closed top of the housing 9 it compresses the trapped air between the top of the housing and the top of the piston. A spring 13 is seated in a depression 15 formed in the piston 11 and reacts against the 50 top of the housing 9 to tend to keep the piston 11 at the bottom of the housing. It is to be noted that the piston 11 also tends to assume a position 55 at the bottom of the housing 9 by the action of gravity.

The housing 9 is preferably cast as an integral piece and comprises a clevis 19 adjacent an opening or slot 20 formed in the wall of the housing for a purpose to be described hereinafter. With 5 this construction the piston 11 traps air at the top of the housing 9 and there is no means for its escape except through a duct 35, provided for that purpose near the top of the housing. As compression takes place above piston no gas- 10 ket is needed between the housing 9 and the base.

A slightly bent lever 17 is provided for each compressor 3 and 5 to operate the associated piston 11. Lever 17 having an end extending through the opening 20 is pivoted substantially 15 midway between its ends by a pin 21 between the sides of the above-mentioned clevis 19. A pedal or toe-piece 23 is formed at the outer end of lever 17 and a contact or rocker portion 25 is formed at the inner end thereof which rocker portion is adapted to engage the under side of 20 said piston.

As shown in Fig. 3, the lever 17 and piston 11 are in their "un-operated" position and the piston 11 by action of gravity and the spring 13 has pushed the end 25 of the lever 17 downwardly until its flat bottom surface 27 is in contact 25 with the base 1 and the pedal 23 is in its raised position. In Fig. 2 the same lever 17 is shown in its "operated" position in which position the 30 pedal portion 23 is held down by the operator's foot and approximately 50% of the lever 17, comprising the lower surface 29 thereof is resting on the base 1. In this way any further pressure of the operator's foot is borne by the base rather 35 than by the piston 11. Thus any tendency to bend or warp the piston 11, by excessive pressure, is avoided.

In this latter position the piston 11 is forced to the top of the housing 9 by the raising of the 40 rocker point 25, and the air trapped between the piston 11 and housing 9 is compressed.

Each lever 17 is so positioned that its pedal portion 23 when in an "unoperated" position is only slightly above the base 1, and when in 45 "operated" position is substantially in the plane of the base. In the present embodiment, for example, the pedal 23 in "unoperated" position is only about three-quarters of an inch above the base 1. At this elevation the ankle of the 50 operator is practically unflexed. Further, the two pedals 23 of the levers 17 are so positioned with respect to each other that the operator's foot, when disposed between the two pedals, may operate them both with the same downward motion or, if it is desired to operate them selectively, the operator may swing her foot to the right or to the left to a position above one of the pedals and clear of the other thereof. This selective 55 positioning of the operator's foot may easily be carried out by simply swinging the foot about the heel placed on the floor. Contact between the sides of the operator's foot and the housing 9, helps to correctly position the foot although such a contact is not necessary.

60 Thus in operation the duplex foot-operated control device is placed on the floor and the toe portion of the operator's foot placed in the immediate vicinity above the pedal portions 23 of the levers 17. The operator may as hereinbefore pointed out operate either pedal or both, or may keep her foot in a slightly raised position above the pedals without assuming an unnatural position. When, however, she does operate one or 65 both of the pedals her foot is substantially flat on the floor.

A metal conduit 31 taps each housing 9 and transmits the pressure created by the compressing action of the piston 11 on the trapped air to the flexible tubing 7. As is clearly shown in Fig. 4 each conduit 31 is secured to the housing 9 by means of a pressure coupling 33 threaded into the housing. The duct or hole 35 in each housing connects the interior of the housing with the coupling 33.

The flexible duplex conduit 7 is connected to the metal conduits 31 as is shown at numeral 37. The conduit 7 is a duplex arrangement having two separate passages therethrough and is formed from rubber or the like. Resilient wire helices 39 are positioned in the passages of the portion of the flexible conduit 7 which is immediately adjacent the base 1, and as shown in Fig. 4 one end of each helix extends into one of the metal conduits 31 to which the tubing 7 is joined. A clamp 41 secures the conduits 31 and 7 jointly to the 20 base 1 and enhances the strength of the joint 37.

The resilient helices 39 not only reenforce the conduit 7 but also tend to prevent kinking of the conduit or tubing 7 which kinking would close the 25 passages and hence render the control device inoperable.

The end of the tubing 7 which is away from the base 1 terminates in two tubes 43 which are of known construction and need no further explanation except to say that they are preferably 30 attached to separate pressure responsive means on the machines controlled.

A corrugated rubber pad 2 is suitably mounted on the underside of the base 1 and serves to provide friction between the control device and the 35 floor so that as the operator uses the control device it will not inadvertently slide around and change its position.

One of the advantages of the invention is that a foot-operated control device has been provided 40 which may be operated without tiring the operator's foot.

Another advantage is the flexibility of control which may be secured with the duplex arrangement. Thus in the event that simultaneous actuation of both of the pressure responsive means 45 on the machine being controlled is desired, the arrangement of the pedals is such that they may be operated simultaneously with one foot.

Another advantage of the invention is the fact 50 that the capacity of the compressing units may be increased by increasing the depth of the housings 9, and without making it necessary for the operator's foot to assume an unnatural position. With the former type of like foot-operated control means, in which the operation of the piston was effected by direct downward movement of the operator's foot, which was placed above the piston, the height to which the compressing unit could be raised to increase the capacity of the 55 unit was limited by the extent to which the operator's foot could operably be raised above a natural position. In the present construction in which the operation of the piston is effected by means of a lever, and in which the toe piece of the lever is considerably below the top of the housing, the toe piece of the lever may be raised considerably above the piston shown in Fig. 3 to increase the capacity without causing the operator's foot to assume an unnatural position.

Another advantage of the invention is that a control device has been provided which has improved points of construction such as reenforcing and kink-preventing means in the flexible 70 75

conduit, and which also has improved construction to prevent leaking of the compressed air.

As various embodiments might be made of this invention, and as various changes might be made in the construction herein described, all without departing from the scope of the invention, it is to be understood that all matter herein set forth or shown in the accompanying drawing is to be interpreted as illustrative and not in a limiting sense.

I claim:

1. A compressor unit for pneumatic foot control devices, comprising, in combination, a member having a cylindrical bore of large diameter relatively to the length thereof and open at one end and closed at the other, a piston in said bore, a lug formed on and extending outwardly from the peripheral wall of said member adjacent the plane of said open end, the lug and contiguous wall being slotted radially with respect to the axis of said cylinder, a radially mounted lever having contact with said piston at its inner

end disposed in said slot and pivotally supported by the bifurcated parts of said lug, and means tending to hold the piston in contact with said lever.

2. A compressor unit for pneumatic foot control devices comprising, in combination, a member having a vertical cylinder bore open at its lower end and closed at its upper end and having a fluid duct disposed adjacent said upper end, a piston in said bore having a cavity formed in its upper surface, an helical spring mounted with one end seated in said cavity and the other end in contact with the closed end of said member, a lug formed on and extending outwardly from the peripheral wall of said member adjacent the lower end thereof, the said wall having a slot formed therein adjacent said lug, and a piston-operating lever disposed in said slot, pivotally supported by said lug and having contact at its inner end with the underside of said piston.
